[57] **ABSTRACT**

Machines have been disclosed for forming a button stay side zipper patch and a fly side zipper patch as garment components for later incorporation into garments such as men's pants; the button stay side machine consists of a combination of elements which

takes separate pieces of zipper patch fed either invertibly or directly to a folding device where the patch is folded and pressed, thereafter joined with a zipper string, and in a serging sewing machine the zipper is sewn to the patch; in a zipper "gapper" device a certain number of zipper teeth are removed from the zipper string and, after a "top stop" placed on the zipper section string for the button stay side patch, the continuous and chained-together button stay side patch is placed in a cutting device where each individual button stay side zipper patch is cut from the others and thereafter stacked; another embodiment of the button stay side zipper patch machine is provided whereby individual patches are preformed in a ribbon and the ribbon is fed to the serging machine without pickup and folding of the individual patches; thus, the present button stay side machine is comprised of means for feeding an individual patch; means for inverting every other patch, if desired, means for folding each patch, means for pressing; means for feeding and sensing the feed of the zipper; means for serging; means for gapping the sewn button stay side zipper; means for placing a top stop on the zipper; and means for cutting each of the individual button stay side zipper components including means for stacking the same; the fly side zipper patch machine comprises a serging machine including means for feeding a ribbon of patches to the same, and a double needle flat bed sewing machine including the means for feeding the patches through it and through the serging machine and means for feeding the zipper string whereby the zipper string is sewn on the patch; further the fly side zipper patch machine includes the gapper means, but not the top stop means, and the cutting and stacking means.

ZIPPER PATCH SEWING AND FORMING MACHINE

This invention pertains to garment component forming machines; more particularly, this invention pertains to a button stay side zipper patch forming machine and a fly side zipper patch forming machine which utilizes heretofore unutilized scrap for forming the zipper patches as zipper garment components. Further, this invention pertains to the various combinations of machine elements which are used for producing and for forming a button stay side zipper patch and a fly side zipper patch as garment components.

FIELD OF INVENTION

In a pants article such as men's pants, a zipper is used for closing a fly. The fly is formed from a fly side zipper patch and a button stay side zipper patch. The fly side zipper patch covers the button stay side zipper and its patch, and thus the zipper as such is not exposed. After the formation of these two garment components, these zipper patches are then incorporated into the pants article by sewing each to the proper side of the pants article.

THE PRIOR ART

In the prior art the incorporation of the button stay side and fly side zipper patch components have required a specially cut strip from a bolt of material which has been laid on a table. Consequently, it has resulted in considerable waste of usable material which could otherwise be employed for better placement of garment patterns. Moreover, the normal scrap which is inherent in the production of any garment components such as pants is still being produced and not being utilized. Thus a costly procedure for producing garment components has been required by the prior art devices.

Additionally, the prior art devices have required a separate operator for running a conventionally unmodified gapper which gaps both the fly side and the button stay side of the zipper. Further, an additional person had to be employed to separate the gapped zipper strings each of which then was sewn into each of the garment components in a separate operation. Still further, the prior art has required a separate machine for patch folding. In this machine a specially cut garment strip is unrolled from a wound up roll, folded and the zipper is fed with it so that the zipper can be serged and cut in other and separate operations. Only after these steps in the various machines and in the described sequence, the button stay side zipper or fly side zipper patch component is incorporated into the garment. As it can be well appreciated, the use of scrap material which does not reduce the material available for actual cutting of the exposed part of the garment, the reduction of the steps in operational sequence, and the elimination of separate machines make the present invention eminently more suitable for achieving considerable savings in the material as well as in the operator time.

BRIEF DESCRIPTION OF THE INVENTION

The present invention consists of a machine which comprises means for holding a stack of patches, means for feeding individual patches of a material to means for folding the patches; means for pressing the folded patch including means for ejecting the pressed patch,

means for feeding a zipper string (also called a zipper tape) and joining the same with the folded patch, means for serging the zipper and the patch and feeding by specifically and particularly controlled feeding means, including sensing means, for feeding the serged zipper and patch into means for gapping the same, further feeding the thus properly gapped zipper into means for placing a top stop into said zipper, and means for severing each of the individually formed button stay side zipper components, including means for stacking the same.

Further, the fly side zipper patch machine comprises means for cooperatively feeding a ribbon of patches to a serging machine and a flat bed double needle sewing machine, including means for feeding a zipper string to the serging and double needle sewing machine, means for gapping the zipper string at a predetermined position on the zipper string, means for cutting the gapped zipper string and its patch and means for stacking the same.

DRAWINGS AND FIGURES

In reference to the drawings and wherein the elements performing the same functions are labeled with the same numerals and wherein:

FIG. 1a to 1f show the stepwise production sequence of the button stay side zipper patch garment component comprising of a zipper string, a facing patch and a top stop;

FIGS. 2a to 2d show the stepwise production sequence of the fly side zipper patch garment component comprising of a facing patch, a backing patch therefor and a zipper string;

FIG. 3 illustrates in perspective the machine for formation of the button stay side patch as one embodiment of the invention and wherein the various component parts of the machine are indicated; however, for sake of clarity, some of the more detailed component parts of the machine have been eliminated or simplified;

FIG. 4 shows the facing patch pickup and transfer section;

FIG. 5 shows in side view the facing folder and press section;

FIG. 6 illustrates in top view the facing folder and press section;

FIG. 7 illustrates in perspective the zipper run-out and zipper jam section;

FIG. 8 illustrates partially in perspective and partially in front view the zipper feed section;

FIG. 9 illustrates in front view the serger sewing machine;

FIG. 10 illustrates in top view the serging machine;

FIG. 11 illustrates in front view the means for guiding a zipper string and patches sewn to it into a gapper;

FIG. 12 illustrates in cross section a zipper teeth turning device shown in FIG. 11 along line 12-12;

FIG. 13 illustrates the gapper die and press section including the means for indexing at half teeth space and the means for proper positioning of the facing patch and zipper in the gapper;

FIG. 14 illustrates in a side view the gapper die and press in its nonengaged position;

FIG. 15 illustrates the gapper die and press in its engaged zipper teeth shearing position;

FIG. 16 illustrates the means for feeding or moving the facing patch and zipper through the various ma-

chines such as in the gapper device after the zipper and patch have been sewn together in the serging machine;

FIG. 17 illustrates in a front view means for attaching a top stop to said button stay side zipper string;

FIG. 18 illustrates in a top view means for attaching the top stop to said zipper string including means for sensing the proper placement of the top stop on the zipper string;

FIG. 19 illustrates a cutting device for the button stay side zipper string including stacking means after the string has been cut;

FIG. 20 illustrates another embodiment of the button stay side zipper patch machine wherein the feed device for patches shown in FIG. 3 is modified to allow feeding of a ribbon of patches to the serging machine;

FIG. 21 illustrates a further embodiment of the invention wherein fly side zipper patch feeding means to a serging machine is shown as it relates to the generic invention;

FIG. 22 illustrates fly side zipper patch machine as it relates to the zipper string and patch feeding and sewing in a two needle flat bed sewing machine.

FIG. 23 is a schematic circuit diagram of the control circuit for the patch pick-up and transfer mechanism of the invention;

FIG. 24 is a schematic circuit diagram of the patch folder and press control circuitry of the invention;

FIG. 25 is a schematic circuit diagram of the circuit for controlling the zipper feed mechanism of the present invention;

FIG. 26 is a schematic circuit diagram of a circuit for controlling the serger mechanism of the invention, and for developing a start signal for equipment downstream from the serger mechanism;

FIG. 27 is a schematic circuit diagram of a circuit for controlling the operation of the puller and gapper mechanism of the present invention.

INTRODUCTORY DESCRIPTION OF THE BUTTON STAY SIDE MACHINE

In reference to FIGS. 1a and 3, the patch shown in FIG. 1a is picked up in the facing patch pickup and transfer device labeled as 30 in FIG. 3 and shown in detail in FIG. 4, then forwarded to the facing folder device 40 shown in FIGS. 4 and 5 wherein it is folded as shown in FIG. 1b. Thereafter the zipper string is run through a zipper jam and run-out device shown in FIG. 7 (not shown in FIG. 3). Subsequently, the zipper string is fed by means of the feed device shown in FIG. 8 (not shown in FIG. 3) and joined with the facing patch, and sewn thereon as shown in FIG. 1c by means of the serging machine 70 illustrated in FIGS. 8 and 9. From serging machine 70, the zipper string with the facing patches attached thereto as illustrated in FIG. 1d is gapped in the gapper device labeled as 90 and shown in detail in FIGS. 13, 14 and 15. A top stop is applied as shown in FIG. 13 in the top stop section labeled as 100 and shown in FIGS. 17 and 18. Finally, the zipper string is cut in the device labeled as 110 and button stay side garment component is stacked by means of a stacking device 120; both devices are illustrated in FIG. 19. Another feed means embodiment for button stay side zipper patches is shown in FIG. 20.

INTRODUCTORY DESCRIPTION OF THE FLY SIDE ZIPPER PATCH MACHINE

In reference to FIGS. 2a to 2d and FIGS. 21, 22, a fly side zipper patch sewing and forming machine has means for proper serging of a patch ribbon to its backing, including means for feeding it thereto as shown in FIG. 21 to produce a patch as shown in FIG. 2a; thereafter the fly side patch is joined with a zipper string by means of zipper string feeder as shown in FIG. 8 under a presser foot of a two needle flat bed sewing machine 713 in FIG. 22 wherein the patch and zipper string is sewn together producing a ribbon as shown in FIG. 2b; the sewing machine is aided by feed means illustrated in FIG. 22. The gapper and the cutter means are those illustrated in FIGS. 13 to 16 as in the button stay side zipper machine. In identifying the work piece in FIGS. 2a to 2d, the same numerals, where applicable, have been used as in FIGS. 1a to 1f.

DESCRIPTION OF THE INVENTION

Returning to FIG. 1a, a pinked patch 10 forms the facing patch used in the button stay side zipper garment component. This patch is pinked on one end 11 as shown in FIG. 1a. The pinking is done in a different machine such as a die cutter by means of which the facing patches are formed. In FIG. 1b the facing patch is shown after it has been folded in half. The folded seam is identified as 12.

The top part of the facing patch is identified as 13 and it has been sewn to it a zipper string 14 which has zipper teeth 15 on the inside and underneath the patch 10. A serging stitch line 16 which holds the patches and zipper together is also shown in FIG. 1c. As the zipper teeth 15 are under patch 10 and in order to gap the zipper string 14, the teeth side 15 of the string 14 is folded outwardly and presented to the gapper for gapping. Thus, when the teeth are facing towards the gapper, the gapper removes a section of zipper teeth 15 from the zipper string 14. This section is identified as 17 and shown in FIG. 1d. Further, the top stop 18 shown in FIG. 1e is placed on the zipper string while the zipper teeth are still folded outwardly. From them on the zipper teeth 15 are folded back underneath the facing patch 10 and then the zipper string 14 is cut substantially coextensively with the leading edge of the patch near the top stop 18 as identified by numeral 19. The cut patch shown in FIG. 1f is in the form in which it is ready for incorporation in the pants.

Turning now to FIGS. 3, 4 and 5 which illustrate the facing pickup and transfer section 30, a motor 150 driving shaft 151 having thereon two pinion gears 153 causes racks 152 to be urged upwardly as guided by bearings 154. To the top of racks 152 is attached table 156 with a stack 157 of patches 10. A front stop 159 for stack 157 is adjustably but fixedly mounted on frame 160 which frame in turn is attached to a pinion and rack frame 161. A back stop 159a is attached to the pick up and transfer device frame 175a. A smooth side guide 156a confines stack 157 and still allows the stack to reciprocate in a trouble-free manner. Side guide 156a is attached to frames 175a and 162. Frame 175a is attached to motor frame 162.

As shown in FIG. 3, the front stop 159 rides in a slot provided in table 164 and the stop 159 can be placed for adjustment on the frame 160 to accommodate various lengths of the facing patch 10.

As motor 150 urges upwardly table 156 with stack 157 of patches 10 thereon the stack, i.e., the top patch engages lever 166 which in turn trips microswitch 167. The lever 166 is pivoted on shaft 169 and is normally urged downwardly by spring 170 abutting against stop 171.

When microswitch 167 is tripped, the electrical control means further explained herein activates cylinder 172 which is a pneumatically driven double acting cylinder, i.e., having a power stroke in forward and rearward direction. Cylinder 172 pulls forward the tape pickup assembly 175.

It is to be noted that upon the upward urging of the stack 157, the small wheel 176 has been engaged with the top most facing patch 10 on stack 157. Wheel 176 carries around it tape 177 which is wound from roll 179 onto roll 180. These two rolls are carried on frame 181 and in turn are mounted via a cross bar 182 on two parallel sliding sleeves 184 mounted on sliding rails 186. Two rails on both sides of the cross member 182 assure a trouble-free and smooth operation for the sliding of the tape pickup device 175.

As engaged by the small wheel 176 and urged forwardly by cylinder 172, the tape held facing patch 10 is further separated by a jet of air emanating from exit nozzle 187 which is placed at an appropriate angle on air nozzle frame 188. The patch 10 is being pulled forwardly upon the movement of device 175.

As secured by tape 177 and when urged by the piston 172, the facing patch is moved forwardly over conveyor rollers 197. When trip bar 200 trips lever 188 on a pneumatic trip valve 189 (and when the pickup and transfer device is in its forward most position), a piston 190, which extends downwardly a rubber tipped rod 191, engages the patch and holds it on platform 192. A downwardly urged link 194 having a spring thereon 195 and wheel 196 engages a patch against the rotating conveyor rollers 197 and thus completes the removal of the facing patch from the facing pickup and transfer device 175. On the forward movement of the pickup and transfer device 175, the same trips also microswitch 199 which actuates the reverse power stroke of cylinder 172 for returning the pickup and transfer device 175 to its original starting position. Upon return to the original starting position the pickup and transfer device 175 engages microswitch 202 which via an appropriate delay means further explained herein initiates another cycle.

The pneumatic valve 189 is mounted on cross member 182. In order to insure that the forward and rearward movement of device 175 is reasonably smoothly stopped, rubber cushion rings 201 are mounted on the slide rails 186 both in the forward and rearward most positions.

The tape 177 is urged and wound up on the takeup reel 180 by means of a sprocket gear 207 which is advanced by ratchet lever 204 urged downwardly by spring 206 and restrained to achieve the stroke by bolt 205. Ratchet 204 is mounted on ratchet lever post 208 and pivots on ratchet shaft 204a. In turn, ratchet lever post frame 208a is attached to pickup and transfer device frame 175a. Sprocket gear 207 is mounted on shaft 210 (carried in the shaft support post 211 which is attached to cross bar 182). The shaft 210 carries on the other end gear 212 which engages gear 214 driving takeup reel 180 as shown in FIG. 4. Thus, upon return stroke of device 175 and before a next patch is picked

up a fresh tape section is presented to the next patch.

A transferred facing patch is being urged along conveyor rollers 197 as shown in FIG. 5. Rollers 197 are driven via chain 241 by motor 241a. Motor 241a is interconnected by appropriate sprockets mounted on a conveyor roller to drive both the upper conveyor rollers 197 and lower conveyor rollers 244 as shown in FIG. 5. The last part of upper conveyor rollers are split to accommodate chute 271 as shown in FIG. 6, and these rollers are again interconnected so that both sets of conveyor rollers are rotating in the same relationship. As the facing patch moves on the upper and lower conveyor rollers, it is urged against a side guide 246 which assures that the facing patch 10 is properly positioned under the facing folder blade 250 or in respect to the serging machine presser foot 376.

In reference to FIG. 3, the item labeled as 35 is a patch turner which turns over every other patch and has been found necessary when the device illustrated in FIG. 4 is used with a stack of patches which are cut from a stack of cloth material alternatively placed face up and face down on a table as is well known in the art. A description of the device is found in U.S. Pat. application Ser. No. 186,986, filed Oct. 6, 1971, which application is incorporated by reference herein.

If the turner device 35 is not used, then the facing patch is sent directly over the chute opening 257 and under the facing folder blade 250 which is attached to cylinder 251 and its rod 252 to a blade frame 253, the last in turn is attached to the blade 250. Frame 269 holds cylinder 251. The blade 250 is urged downwardly by a double acting cylinder as guided by rods 254 when a facing patch interrupts a beam from a light to a photocell, the combination of which is shown as 256 in FIG. 6. As initiated thereby, the blade is urged downwardly into the slot 257 which accommodates the blade as well as a facing patch.

The rapidity of the down stroke as well as the confined slot 257 assures that the facing patch resides in the same without falling through. However, the bottom portion of the facing patch as defined by seam 12 does protrude below the slot 257. Shown in FIG. 6 in phantom lines is a patch approximately the extent of slot 257 and a heated press section for a patch. A patch residing in a folded form in slot 257 is pressed by urging section 258 against a permanently positioned heated press 259 for the facing patch.

The force on the movable section 258 is exerted by two pistons or cylinders 260 mounted on frame 261. After an appropriate delay time, which will be further explained herein in reference to the control means, the double (or single) acting cylinders are retracted and as retracted by a spring 258a, bar 258 slides in its guide rails 260 (not shown but underneath bar 258) thereby opening again slot 257. If need be, as it is encountered with a number of fabrics, the folder blade 250 may be urged downwardly once more to eject the folded patch from slot 257. The upward position of the retracted folding blade 250 is detected by a microswitch 267 activated by microswitch trip lever 267a affixed to rod 254.

The press section is mounted on the underside of the frame 197a by two cross bars 270 to which are also attached a chute 271 on which the folding patch slides downwardly and onto the lower conveyor rollers 244. Thermometer 270a indicates the press bar temperature.

As shown in FIG. 6, the slot 257 interrupts the conveyor roller drive under the blade 250 and the conveyor rollers are driven on each side of the slot 257 by means of the interlinked chains illustrated in section and in phantom lines in FIG. 5. The upper conveyor section with rollers 197 is spaced apart from the lower section rollers 244 by means of spacer posts 275 which are placed on a suitable table 32.

Attached to the left most spacer bar by means of a post 280 is zipper carry over bar 281 which serves as a guide for the zipper string from the zipper run-out and zipper jam section 50 shown in FIG. 7 to the zipper feed section 60 shown in FIG. 8. The zipper feed mechanism and the means to monitor the proper feeding of the zipper will now be explained in reference to FIGS. 6, 8, 9 and 10 in conjunction with the feeding of the patch which has been folded and urged on the lower conveyor rollers 244 towards the serging machine device 70.

As the zipper is being pulled out by the zipper feed section 60 from a suitable receptacle (not shown), it is pulled through the zipper run-out and zipper jam section 50 illustrated in FIG. 7. This section is attached to the table 32 by means of a post 284 having a member 286. Member 286 holds shaft 287 on which lever 290 pivots and which is restrainingly adjusted by means of block 289 abutting table 32. Attached fixedly to lever 290 is frame 294. A swinging fold plate 297 in turn is attached to frame 294. Between the fold plate 297 and frame 294 is a gap 292 in which the zipper is being fed. The fold plate is restrained by a spring 300 mounted on screw 299, and it pivots on the shaft 291. Mounted on the fixed frame 294 is a microswitch 296 which, when it does not sense a zipper string in gap 292, indicates a run-out of a zipper string. A handle 301 is conveniently provided to open up the fold plate 297 and feed the zipper string into gap 292.

If the zipper, as it is being pulled from the receptacle upwardly, jams the microswitch 303 (mounted on angle bracket 302, attached to table 32), it is activated. Thus when the bar 290 releases the pressure on the microswitch 303, it signals a failure in the proper feeding of the zipper string. The downward movement of the frame 294 is restrained by the angle section 304 mounted on the angle bracket 302 thus assuring the proper working engagement of the microswitch 303.

As the zipper from the zipper run-out and jam section 50 mounted on the front side of table 32 is being fed over the conveyor 244, the guide bar 281 is properly positioned to lead the zipper string to the feed section 60 shown in FIG. 8 and placed on the back side of table 32. The feed section 60 is mounted on table 32 by a post 310. A plate 311 holds the various drive and control means for the zipper string. Attached to plate 311 is a positioning block 312 on which guide roll 314 has been askewingly mounted to lead into the drive wheel 316 a zipper string. Drive wheel 316 is driven by motor 317. The guide wheel 316 may have an appropriate groove cut into the same (not shown) in which the zipper teeth are being lead.

As the zipper from the other side of guide roll 314 is being fed upwardly and around the periphery of the driving roll 316, the zipper is engaged by a driven roll 319 mounted on a lever 320, pivoted at 321, and urged downwardly by spring 322 against drive roller 316. Guides 324 which are small angle sections assure that the zipper is being fed downwardly and not reengaged

with driving roll 316. As the zipper moves downwardly behind a Plexiglass cover 326, it forms a loop between the photocell and photocell lamp combination 327 and 327a, respectively, and then moves upwardly into a grooved idle roller 329 rotating on shaft 330. Guide 328 prevents the zipper string from being wound up around roll 329.

As the zipper moves downwardly and it is guidingly lead towards the serger sewing machine device 70, the zipper string is passed under two grooved guide rolls similar to 314 and identified as 331 which are mounted on a projection 334 attached to the table 32. These grooved rolls rotate on shaft 332.

As the facing patch travels on the lower conveyor rollers 244 shown in FIG. 9, it approaches the photocell lamp combination 372 illustrated in FIGS. 5 and 9. As the photocell and a delay circuit further explained herein signals a "start-sew" condition for the sewing machine 370, and as the zipper is lead around the feed guide rollers 331, under the sewing machine 370 feed guide 377 and presser foot 376 as a continuous string, the sewing commences immediately and proceeds along table 374. As shown in FIG. 9, sewing proceeds leftwardly (or as shown in FIG. 10, the top view of the sewing machine 370 from top on down) as indicated by the arrow. The sewing machine is a conventional Union Special Serging Machine and is readily available on the market.

The modifications in this machine consist in the presser foot 376 and throat plate 381 being grooved to accommodate the zipper string as well as the zipper teeth. Further, the modification also consists in a larger presser foot 376 which is shown in FIG. 10. Presser foot 376 guides as well as properly engages the facing patch as it is being lead into the machine by the conveyor rollers 244.

As is conventional with the serging machines, the presser foot 376 also can swing outwardly via presser foot pivot point 379 for easy access to the needle 382. The presser foot tension adjuster 383 has also been shown in FIG. 9.

The machine is conveniently mounted on the table 32 on resilient pads 371. As the facing patch and the zipper string after sewing together are being urged by the feed dog 380 through the sewing machine 370 and in order to assure a constant feeding force so that there is no tension on the zipper and facing patch, a feed control wheel 390 is driven by means of intergeared connection (not shown) from the sewing machine at a synchronous rate with the feed dog. The drive wheel 390 controls the proper tensioning so that no improper distortions of the patch or zipper string occur in the sewing machine.

A rubber driven or engagement roll 391 off-center and spring engageable such as shown in FIG. 9 and illustrated by the lever 392 and off-center shaft 391b, in respect to shaft 391a, controls the proper exertion of the pressure on wheel 390 and thereby the feed.

As sewn zipper and facing patch emerges from the two rollers 391 and 390, it proceeds onto the sheet metal guides 396 mounted on table 32 and shown in FIG. 11. Although there are three substantially identical guide units on the machine illustrated in FIG. 3, only one has been shown in detail in FIG. 11. As illustrated, a channel member 394 is utilized to attach the guides 396 to table 32. A string of patches held by the zipper string is trained around grooved wheel 397

which is mounted on a block 399 riding on a pair of guide rails 400. Wheel 397 is partially counterbalanced by weight 401 suspended from wire 406 trained around a pulley 404 and attached to the frame 409 in which the guide rails are mounted. The frame comprises U-shaped channel member 410 in which the weight 401 is confined.

An upper and lower limit microswitch 402 and 407, respectively, define the extent for wheel 397 travel and are positioned for proper operation of the machine so that subsequent downstream machine operations are not affected. Thus when wheel 397 does exert on the zipper and patch string a positive downward pressure when the serging machine 370 is sewing and the gapper device 90 is not operating, it trips microswitch 407 by means of trip plate 399a which stops in an alarm mode the gapper device 90 as well as serging machine 370 from operating, i.e., employed in combination with the positive feed control wheels 480 and 481 shown in FIG. 16. This assures proper sequential operation of the machine. However, when trip plate 399a trips microswitch 402, if the serging machine has not kept pace with the gapper device 90, then the gapper device is stopped and the serging machine is allowed to keep pace. However it has been found more advantageous to stop the serging machine 370 as well. Similar and interconnected operation is provided with the other downstream guide unit interconnected operations.

The guide units 85 depicted in FIG. 11 are employed between the gapper section and the top stop section as well as the cutting section; the description of these units will not be repeated; however, it is to be understood that the function of these are the same except that associated with the zipper turner.

As the facing patches and zipper string proceed upwardly around the periphery of wheel 397, a twist is imparted to the zipper string as it is being fed into a zipper peeler or zipper turner 411 also illustrated in cross section FIG. 12. Zipper turner 411 consists merely of a guide 411a placed on block 411b which projects the zipper outwardly as shown in FIG. 1d and projects it properly for engagement with a gapper by means of a zipper teeth holder gap 411c. In turning the fly side zipper string, a twist is given to the fly side patch ribbon and then the zipper teeth are lead into the gap 411c.

From the zipper turner 411, the patch and zipper string are guided onto the upper part of curved guide 396, on the gapper side thereof as shown in FIG. 13. A ledge 431 is provided for the patch and zipper string for leading it past a "slow-pull" photocell and photocell lamp combination 430 and 430a, respectively, and into a zipper teeth guide 432 which confines the zipper string. As shown in FIG. 13, a slot 433 is provided for the zipper teeth guide 432 which confines zipper teeth for proper positioning in the gapper die and press section further explained below.

As the individually sewn and chained together zipper patches go past the slow pull photocell 430, it is sensing the leading edge of the patch. The stop photocell 434 and 434a also is sensing the leading edge of the patch. By the combination of the two photocells and the drive unit 80 shown in FIG. 16, the zipper string is properly positioned for gapping in the gapper section 90. The gapper section 90 consists of two parts, the die section 438 and the press section 437 and shown in FIG. 13. The gapper is a conventionally available gapper press, but its press and die parts are modified to suit the par-

ticular gapping condition and gapping requirements necessitated by the present operation of the fly side and button stay side zipper patch formation and production. The gapper which is shown in FIG. 13 is a conventional five-ton press available from Alva F. Allen Co., Clinton, Missouri.

The gapper and its presser section as shown and illustrated in FIGS. 13, 14 and 15 consists of a press block 422 to which is attached press land 439 having a gap 440 which accommodates the zipper teeth in such a relationship that these are cut off where the two zipper teeth legs straddle the edge of a zipper ribbon.

The cutting is achieved by means of a shearing action exerted by die 446, and more specifically its die land 445 shown in FIGS. 14 and 15. For proper positioning, the zipper string is lead into the press section by means of a first guide 432 and its aperture 433 and a second guide 436 and its aperture 436a. These two differ one from the other in that as shown in FIG. 14, a cross section along line 14 of FIG. 13, the second guide has a spacer 435 whereas the first one 432 has no spacer. The latter confines the zipper teeth almost abuttingly against the vertical section of the guide 432 in the slot 433.

For proper positioning of the teeth so that the die 446 does not cut a single zipper tooth in the longitudinal midsection thereof, i.e., the long axis of the zipper tooth, a tooth positioner 460 has been placed in the clamp block 444 and it operates as follows. As the clamp block 444 is being urged downwardly by means of the reciprocating die plate 456, springs 450, one on each side of the die 446, are initially not compressed and are guided by the spring rods 449. The clamp block 444 is confined and attached to the die block by confining guides 446 which in turn are affixed to the die blocks 451 one to each side thereof by means of spacers 443. When urged downwardly, the clamp block 444 causes the zipper tooth finger 466 to go into a gap between two zipper teeth and move or urge forwardly the zipper string upon the engagement of the zipper tooth finger 466 with the upper surface 439a of the press land. Thereafter the camming action which is exerted by the clamp block protrusion 444a shown in FIG. 13 on the surface 464 of the finger causes the finger 466 to act as a cam and gently move a zipper string to the leftward position on the press section as shown in FIG. 13. As the spring 462 is being compressed against the pin 461 inserted in the clamp block 444, the proper positioning of the zipper in terms of its gapping position has been achieved.

However, in respect to the facing patch, the proper positioning of the zipper is achieved by means of the two sets of photocells and lamps 330, 330a and 334 and 334a, respectively, as it will be further discussed in reference to the photocell and control means disclosed herein and in reference to the gapper puller shown in FIG. 16. When the clamp block has engaged the zipper, springs 450 are being compressed and the die 446 via die land 445 shears off the zipper teeth along shear face 441 of the press block 439.

Upon the retraction of the die 446, a suitable air jet (not shown) may be provided which by means of the air blast removes the sheared teeth from the gapped section of the zipper string.

The die 446 is attached to the die block 451 by means of bolts 452 and the die block 451 is in turn attached to a die block and clamp spacer 454. The whole

assembly is suspended from the die plate 456 upon which the force is exerted and rides on posts 457 as guided by post collars 459 as is conventional in an Alva F. Allen press. A press base 437a shown such as in FIG. 13 is placed on table 32.

The proper placement of the gap in respect to the preceding and following facing patch are rather critical in the subsequent sewing of the button stay side garment component pants article. Moreover, as the same principle and device is employed with the serging machine, the gapper, the top stop and the patch string cutter device shown in FIGS. 3 and 19, it will be described as applies to the gapper and further described in variations in respect to the other elements of the machine with which the gapper puller shown in FIG. 16 is operated in conjunction with the two sets of photocells shown in FIG. 13—that is, photocells 430 and 434.

Thus, gapper puller shown in FIGS. 3 and 16 as device 80 exerts its action when the serging sewing machine starts sewing. The controlled, interconnected pulling operation is accomplished as follows. Motor 484 which is a conventional sewing machine drive motor known as a "transmitter" is engaged by means of pneumatic cylinder 486 shown in FIG. 18 acting on lever 487. When the cylinder 486 engages the motor 484, it also disengages the microswitch 490. Belt 489 drives clutch assembly 494 (commonly available transmitter clutch assemblies) causing the engaged clutch 491, coupled to the gear box 500 via belt 492 running over pulley 501, to drive the shaft 487 and thus the gapper puller wheel 480.

The zipper chain and the facing patch are engaged to puller wheel 480 by means of a rubber covered driven wheel labeled as 481 off-center mounted as discussed in reference to driven wheel 391 in FIG. 9, both of which are mounted in drive and driven wheel post 480a. The pulling action is continued at regular speed, until the slow pull photocell 430 and lamp 430a is uncovered and is covered again. The slow pulling action is achieved when the transmitter 484 comes to a stop, i.e., after the motor is disengaged by the pneumatic cylinder 486 and the microswitch 490 has been tripped. The microswitch tripping allows for the start of the slow pull motor 497. The slow pull motor drives via pulley 496 and belt 496a clutch assembly 491 and thus the wheel 480 at a reduced rate. When the slow pull photocell and lamp combination 430 and 430a is covered again by the leading edge of a new facing patch, the motor 497 is engaged coupling the slow pull motor to gear box driving the puller wheel 480 at a reduced speed, and it continues to pull until the second photocell becomes uncovered, i.e., photocell 434. At that time a timing interval is started, which allows the zipper chain to come to a proper positioning for gapping. At the end of the timing sequence, the motor 497 is disengaged; and because the transmitter 484 has been stopped, i.e. braked, the transmitter 484 engages the clutch assembly 491 in a very positive manner and stops it immediately. This event provides for the activations signal to the gapper and the gapping is achieved as described in conjunction with the gapper section 90.

The same operational sequence is followed in respect to the top stop device 100, which will be further discussed herein and in respect to the cutting device 110 each of which causes the puller wheel 480 of which there are one for each of the sections to be engaged by means of a first and second detection device which may

be microswitches or feeler fingers connected to microswitches.

After the gapping operation, the gapped zipper string with the patch string sewn thereto moves around a guide wheel device 85 in a similar manner as was discussed in respect to FIG. 11 and in a similar manner activates and controls the top stop mechanism. The chained zipper string and patch is thus guided into the top stop apparatus shown in FIGS. 17 and 18 as 100.

10 A guide surface 396 allows the chained together zipper and facing patch to move into the zipper teeth guides 542 on both sides of the top stopper; the top stop mechanism is identified as 555 in FIGS. 17 and 18 and the trigger means therefor as 538. These zipper 15 teeth guides are similar to the zipper teeth guides shown in FIG. 13 as 432. The top stopper is a conventional machine such as available from Talon Corporation.

However, it is modified and consists in the means of 20 activating the top stopper including means for slowing and stopping the same for proper placement of the top stop wire clamp 18 which is affixed to the zipper teeth side of the edge of the zipper string as shown in FIG. 1e.

25 Thus, when the cylinder 532 is normally retracted, it projects a pin 537 abutting against a lug 539 in wheel 531. Wheel 531 is belt driven by a motor 533. The lug 539 is a means for clutch engagement by means of pin 537, and the clutch (not shown in detail) in the top stopper wheel 531 is disengaged. As soon as the first or 30 slow pull microswitch lever 540 is activated by feeling the absence of zipper teeth in the gapped section, lever 540 which is an angled lever, pivoted at pivot point 540b is urged upwardly by spring 547 thus tripping microswitch 548 by means of trip pin 540a, the latter then 35 activates the sequentially programmed activation of wheel 480 as described in the connection with the gapper section 90. The slow down of the zipper string with the gap therein is felt by the second or stop microswitch 40 lever 541 pivoted at 541b which stops by means of the same type of activation de-activation as for microswitch 548; the second microswitch 549, by means of trip pin 541a which then causes the cylinder 532 to extend rightwardly the leverage links 534, 535 and 536 45 remove pin 537 from engagement with the lug 539 and thereby activates the top stop mechanism 538 and thus 50 the top stop device 555, placing a top stop wire 18 in the zipper string. The top stop is placed on the zipper string by means of the device designated as 555 and not shown in detail as it is done in the conventional manner by the Talon Corporation top stop device and thus 55 need not be discussed herein.

As the zipper string with the top stop placed thereon moves leftwardly, as shown in FIGS. 17 and 18, it passes through a longitudinal and horizontal slit 556 of a cam lever 557 pivoted on a shaft at a pivot point 558. The lever 557 is held in a ready-to-detect position by spring 557a, and the horizontal slit 556 senses the presence or absence of a properly placed top stop on the zipper string, and hence the proper production of the work piece, when a top stop is on a zipper string microswitch 560, is activated. If a top stop has not been placed on the zipper string, then an alarm is sounded and the machine is stopped.

From the top stop detector unit, the zipper string passes through the fore-mentioned puller wheel 480 the same as shown in FIG. 16 and decends downwardly

around a guide wheel device 85 such as shown in FIG. 11 to proceed upwardly into the cutter device 110 shown in FIG. 19. For the fly side as well as the button stay side patch ribbon, a twist imparted to the ribbon returns the zipper string to its proper place and allows the proper cutting of the cloth zipper string and the patch backing. In this cutter device shroud 396 carried a guide 571 which leads the zipper string with the facing patches attached thereto past a slow pull photocell 572 into engagement with the driven wheel and driving wheel combination as shown in FIG. 16. Undergoing the same sequence of sow down and stopping in combination with the photocell 572 and its lamp 572a (not shown in FIG. 19) and the photocell 574 and photocell lamp 574a (the last two not shown in FIG. 19) and the electrical control circuit as in reference to the gapper section, the cutter device 110 serves each of the facing patches and zipper strings sewn thereon in proper length as shown in FIG. 1f for further incorporation in the garment.

The knife section 110 is attached to the conveyor 587 by means of two upright posts 577 carrying a cross member 579 on the top thereon in which is mounted a knife cylinder 580 having attached a guillotine-type knife 584 at the end of the cylinder rod 585. When the knife 584 is urged downwardly by the cylinder 580, it severs on anvil 586 the zipper string at the proper place in the gapped section of the zipper string.

Thereafter, the conveyor 587 driven by motor 587a (not shown) through an interlinked chain (not shown) sends the cut facing patch against an end stop 590. When the cut patch interrupts the light between the photocell 591 and photocell lamp 598 combination, a stacking grid iron 592 driven by a pneumatic cylinder 594 driving a rack 596 causes a pinion 596 on the stacking grid iron axis 597 to rotate and deposit the patch in tray 599 which has a shelf 598 and stack rods 600 for confining the patches therein.

The following completes the description of the mechanism means for the first embodiment of the button stay side zipper patch forming machine which accomplish the proper feeding, folding, pressing, serging, gapping, top stopping and cutting of the button stay side zipper patch.

In FIG. 20 another embodiment of the button stay side zipper machine has been disclosed which illustrates the feeding of a string of patches attached to a continuous ribbon of a backing material by means such as a glue or sewing. Except for the means for feeding the patches to the sewing machine, the button stay side machine is in all other respects the same. As illustrated in FIG. 20, a free wheeling disc 701 has been placed on an axis 702. If desired, a slight retardation against excessive rotation may be applied against disc 701 such as by means of a spring adjustable brake (not shown). A rolled up string of patches 701a is placed on axis 702 which is then lead to a vertical post guide 704 which is attached to a post 705, also holding the zipper string guide 281. Vertical post guide 704 includes a smooth pin guide 706 which is attached to post guide 704 and through which runs the ribbon of patches with the backing attached thereto. Post guide 704 also holds a run-out microswitch 708 indicating the lack of patches when the pressure by the patches relieves the pressure on the microswitch. Thereafter, an edge rounded rectangular cone guide 707 having a slit in the bottom (not shown) and also having a lead on ledge 709 confines

the patch string in a shape which allows the serging of zipper string to one edge thereof. The zipper run-out device 50 and the zipper feed device 60 are the same as described previously. The modification of the feed section allows production of the ribbon of patches at a location remote from the machine. As the backing material for the patches is reasonably "transparent" to the photocell lamp or photocell and the sensing intensity of the photocell and beams from lamps can be adjusted to detect the edge of the patch, the use of the heat attachable backing provides a convenient means for employing other feed devices with the basic machine.

A machine illustrated in FIGS. 21 and 22 is another embodiment of this invention, i.e., a machine which is used to produce fly side zipper patches for subsequent incorporation in a pants article. This machine differs from the button stay side machine in that no top stop is used on the fly side of the zipper; and in sewing the zipper, it is placed on the patch away from the edge thereof as shown in FIGS. 2a to 2d. However, one edge of the patch is still serged. Thus, the fly side machine may be used in a modular interchange with the button stay side machine. For example, the fly side zipper patch machine may be operated with the same type of serging machine as the button stay side zipper patch machine. However, the fly side patch is made invariably with a patch backing. In line with the above, the devices which are not used with the fly side machines but are used with the button stay side machine may be rendered inoperative, and only the front end of the button stay side machine may be changed. In FIG. 21 the embodiment shown therein illustrates a vertical disc 720 which operates in a manner similar to the horizontal disc 701 shown in FIG. 20. Disc 720 is affixed to shaft 720b which also carries a wound-up roll of a ribbon of fly side zipper patches; for purposes of FIGS. 21 and 22, the ribbon is identified as 720a.

In reference to FIG. 21, a guide bridge 650 on guide platform 651 confines with the aid of a side guide 652 the ribbon of patches 720a as it is fed onto the bed 374 of a conventional serging machine 370 previously described. In order to guide the ribbon 720a onto the serging sewing machine bed 374, a bed guide 654 projects spacedly apart over the bed 374. A microswitch 655 signals a run-out condition of the patch ribbon 750a when its normally closed condition is relieved. A bracket 656 affixed to guide bed post 657 supports microswitch 655.

A modification has been provided for the serging sewing machine 370. Instead of the serging machine being puller wheel aided such as shown in FIG. 9 and which puller wheel pulls intermittently the patch and zipper string in cooperation with the feed dog 380, a single needle, modified as a two needle, flat bed 54,600 Union Special sewing machine labeled as 713 as shown in FIG. 22 is puller wheel aided, and it also aids the serging sewing machine 370. The puller wheel 480 is intergeared with the flat bed sewing machine 713, is intermittently operated and is stopped when the sewing machine is stopped. The intergearing is conventionally known and available and identified as 713a. A zipper feed device 60, illustrated in FIG. 8 and also shown in FIG. 22, is used with a flat bed sewing machine 713.

As shown in FIG. 22, in order to accommodate the zipper teeth, the presser foot 710 of the two needle sewing machine 703 has been modified by a groove 711 (not shown) in the underside thereof. Further, a pair of

side guides 712 are placed on both sides of the presser foot 710 above the throat plate for confining the patches therebetween. Additionally, the upper, driven roller 481 such as shown in the device in FIG. 16 has been modified for disengagement by lever means when the presser foot of the machine is sought to be raised and the puller wheel disengaged.

In reference to FIG. 22, the upper horizontal frame member 714 is attached to the top of the sewing machine head. The vertical frame member 716 is attached to the left side of the sewing machine. A shaft 717 on vertical frame member 716 is provided for pivoting the disengage lever 719. To the lower part of idle roller lever frame 718 is attached main spring 723. Spring 721 is attached to disengage lever 719. Spring 723 is adjustably attached to vertical frame member 716 by bolt 724. A handle 726 is the means by which disengage lever 719 acting as cam on frame 718 is used to engage and disengage the roller 481. For example, as shown in FIG. 22, roller 481 is in engaged position. Frame 718 in disengaged position is held in place by means of spring 723. Spring 721 prevents the disengage lever from rattling when the driven wheel 481 is engaged with the driving wheel 480. Driving wheel 480 is preferably shaped to accommodate the zipper teeth.

In operating the fly side machine it has been found that having a disengaged presser foot before the sewing cycle is very helpful. Hence, a pneumatic cylinder (not shown) is provided which keeps the presser foot up except when sewing; when sewing is initiated such as by a microswitch 402 on a guide device 85 in FIG. 12, the presser foot is dropped.

After sewing the zipper to the fly side patch, the zipper is gapped in the modified gapper previously described and then cut, and stacked by means of the devices mentioned above.

The fly side zipper patch machine can also be used with the device in FIG. 4 instead of the feed device as shown in FIG. 21 and 22. In order to join the backing material to the patch, a rake device shown in U. S. Pat. No. 3611961 and labeled as 230 therein and assigned to the present assignee as the application herein, can be used for this purpose. However, the serging machine as shown in FIG. 21 as 370 is made to operate independently from the flat bed sewing machine 713; i.e., without the puller wheel aided through sewing machine 713.

Either pre-cut or individually formed backing patches may be fed into the fly side zipper machine by means such as illustrated in U. S. Pat. No 3611961 in FIGS. 4 to 6 and FIGS. 7 to 10. The folding device shown in FIGS. 5 and 6 herein is not used and hence the conveyor 197 from the facing patch pick-up and transfer section conveys the patch directly into the serging machine 370, except as modified by the mating means disclosed in the above U. S. Pat. U. S. Pat. No. 3611961 is incorporated by reference herein.

PATCH PICK-UP AND TRANSFER CIRCUIT

The electrical circuitry used to control the patch pick-up and transfer mechanism shown in FIGS. 3, 4 and 5 is shown in FIG. 23. In drawing the circuit, the conversion has been followed that all contact arms of switches and relays are shown in their "normal" positions; that is, if the switch or relay is normally open, the contact arm is shown in its open position, and vice-versa.

Referring now to FIG. 23, the operation of the patch pick-up and transfer mechanism is started by either the manual operation of a start switch 802, or by automatic recycling circuitry to be described below. In both the 5 manual and automatic start modes, +26 volts DC is applied to a point 803 in a storage and switching circuit 804 which charges a capacitor 810 through a resistor 808. A transistor 806 forming a part of the circuit 804 is connected as shown to the resistor 808, and is turned 10 off whenever 26 volts is applied to point 803.

When switch 802 is released to remove the 26 volt signal from point 803, and assuming that transistor 860 is turned on, as it normally is, transistor 806 suddenly turns on and conducts the stored charge from capacitor 15 810 through its emitter-collector path to the gate lead of a silicon controlled rectifier (SCR) 814 connected through a bias resistor 812 to ground. If the carriage-forward limit switch 199 is in its normal condition, with the contact arm at terminal 818, relay coil K₁ is energized. The carriage-forward limit switch 199 will be in the condition shown and capable of operating K₁ at all times except when the carriage is in its most forward position. Since initially the carriage is at its most rearward position, the switch 199 initially is in the condition 20 shown in FIG. 23.

The energization of coil K₁ switches relay contacts K₁ (in the lower left-hand corner of FIG. 23) to connect the carriage-forward valve solenoid 844 to 117 volts AC, thus energizing the carriage-forward valve to drive 25 the cylinder 172 (FIG. 5) and start moving the carriage forward.

When the carriage reaches its forward position, it actuates micro-switch 199 (FIG. 4) and opens it, thus de-energizing coil K₁ and returning the contact arm of 30 relay K₁ to its initial position. This energizes the carriage return valve 842 of the cylinder 172 so as to start returning the carriage towards its starting position.

Operation of the carriage-forward limit switch 199 temporarily causes the application of +26 volts DC to 35 terminal 820 of a delay switching network 822. The 26 volt input is applied through a bias circuit including a DC blocking capacitor 824 to deliver a pulse to the gate of SCR 826. This turns on the SCR 826 and connects a lead 832 to ground through its anode-cathode 40 path.

If the patch stack "up" micro-switch 167 (also see FIG. 4) is in its normal condition as shown in the drawing, the grounding of lead 832 grounds the lower side of the relay coil K₂, shown in the lower central portion of FIG. 23, so as to energize the stack control motor 150 with 117 volts AC and cause it to start moving the 45 stack of patches upwardly.

After a pre-determined length of time (e.g. somewhat 50 less than one second) a delay circuit 830 (e.g. a unijunction timer) supplies a signal to the cathode of the SCR 826 which turns that SCR off, disconnects lead 832 from ground, and thus de-energizes the coil K₂ and 55 stops the stack control motor. Thus, the stack control motor has moved the stack upwardly by a short distance at the start of the carriage return movement. The purpose of this is to move the stack to a position in which it can finish its upward stroke quickly after the carriage has returned to its initial position, and thus reduce the operating time of the pick-up and transfer cycle.

During the period of time when the SCR 826 was turned on, transistor 828 also was turned on and thus

conducted 26 volts DC to a storage circuit 804 identical to the storage circuit 804 in the left-hand portion of FIG. 23. The capacitor of circuit 804 is charged-up while the SCR 826 is on. After SCR 826 is turned off, the charge remains stored in the capacitor 810 until terminal "z" is connected to ground by the operation of the carriage return micro-switch 202 (in the left-hand portion of FIG. 23) upon the return of the carriage to its starting position. When this occurs, the stored charge is delivered through an output lead 838 from circuit 804 to an SCR 836 which again connects relay coil K₂ to ground, energizes contacts K₂ and once again starts the stack control motor to move the stack upwardly.

In this manner, the stack control motor 150 is restarted when the carriage returns to its starting position.

When the stack of patches reaches its uppermost position, the "up" limit micro-switch 167 is actuated to remove the energization from coil K₂ and stop the stack control motor 150. The operation of switch 167 also applies 26 volts DC to a timing circuit 834 which connects the coil of a relay K₃ (in the lower right-hand portion of FIG. 23) to energize the reversible stack control motor 150 and start it turning in the opposite direction to return the stack downwardly.

The timer 834, which is of conventional construction, maintains the energization of K₃ for a pre-determined length of time, thus returning the top patch remaining on the stack of patches to approximately the same position at the end of every cycle. This is advantageous in that the time required for the stack to move to its upper position is minimized and made substantially uniform, despite the very substantial variation in the height of the stack of patches. Thus, the height of the stack is automatically compensated for by means of the invention.

When the "up" micro-switch 167 is actuated, +26 volts DC is applied as a pulse through a capacitor 839 to a conventional timer circuit 840. After a pre-determined time delay, the timer 840 connects relay coil K₄ to ground so that it is energized by the 26 volts supply applied to its opposite terminal. The contacts K₄ (in the lower right-hand corner of FIG. 23) operate then to energize the air blast valve solenoid 187 (also see FIG. 4) to develop an air blast which tends to separate the top patch from those beneath it, as has been described above. After a pre-determined time delay, the timer 840 disconnects coil K₄ from ground, deenergizing the air blast valve solenoid 187 to stop the air blast. Subsequently, the stack control motor 150 turns off and one cycle of operation has been completed.

At the end of the foregoing cycle, a patch has been removed from the top of the stack and is gripped by the adhesive tape pick-up and is ready to be transferred.

As it was noted above, the next cycle of operation can be initiated by the manual operation of the start switch 802. However, it usually is preferred to start the next cycle automatically. The means provided for this purpose includes an oscillator 850 (shown in the upper left-hand corner of FIG. 23) which supplies a brief pulse once every 4 seconds, or at whatever other time period is required to complete a cycle of operation. The output pulse is supplied to a switching transistor 858 whose output pulse is supplied to a switching transistor 858 whose output is delivered to point 803 to ini-

tiate a cycle of operation in the manner described above.

A switching circuit 852 is provided which supplies +26 volts DC on its output lead "b" to the contact arm 5 of relay contacts K₁₇. The automatic recycling circuitry will operate only if contact arm K₁₇ is in its lower position, in order to deliver 26 volts to the emitter of the switching transistor 858.

The coil of relay K₁₇ is shown approximately in the 10 center of FIG. 23. It is energized by manual operation of a switch 846 to energize the coil K₁₇. The momentary operation of switch 846 closes the relay contacts K₁₇ just above the switch 846, and this latches the relay K₁₇ on as long as relay contacts K₁₈ are in the condition 15 shown, and the manual switch 848 is in its position shown. Relay K₁₈ will normally be in the condition shown in FIG. 23 unless there is a malfunction in the system.

Another safety feature of the pick-up and transfer 20 circuit is provided by the fact that the switching circuit 852 in the upper left-hand corner of FIG. 23 is disabled so as to prevent the starting of another cycle until an input signal is received on terminal 897 from the photo-cell circuit 866 (in FIG. 24) indicating that a patch has 25 been received at the folding and pressing station. Thus, additional cycles of the patch pick-up and transfer mechanism will not be started until there is a need for the next patch. This feature enhances the ability of the mechanism to operate automatically without jamming.

30 Further safety features are provided by the transistor 860, the delay circuit 852 and the circuitry connected to the input of delay circuit 852. A new cycle of operation cannot start unless transistor 860 is turned on. It will be turned on by the application of a positive voltage from the +26 voltage DC supply through the delay circuit 852 to the base of transistor 860. However, this bias circuit will be disabled if the input lead to the delay circuit is connected to ground. This can happen in any 35 of three different events.

40 One such event is if the carriage return switch is in the position shown in FIG. 23, thus indicating that the carriage has not been returned to its starting position. Transistor 860 also is turned off by the connection of the lead wire "x" through the timer 834 in the upper 45 right-hand corner of FIG. 23 to ground. Thus, a new cycle of operation cannot be started if the motor 150 is moving downwardly. Similarly, transistor 860 will be turned off if the lead "y" is connected to ground through the SCR 836 when the motor 150 is moving 50 the stack upwardly.

The above safety feature circuitry therefore prevents the starting of a new cycle if either there has been no demand for a patch, as evidenced by a signal on lead 897, or if the carriage is not in its starting position, or 55 if the stack is moving either up or down.

The patch pick-up and transfer circuit described above is similar in many respects to the transfer system described in columns 9-15 and FIGS. 7, 8 and 14-20 of U.S. Pat. No. 3,611,957, which is assigned to the 60 same assignee as this patent application. The foregoing disclosure hereby is incorporated herein by reference.

Certain circuit details have been omitted because they are known in the art and conventional. For example, suitable delay and timer circuits are shown in the 65 aforementioned U.S. Pat. No. 3,611,957, and in other prior art.

The electrical circuit for controlling the patch folder and press equipment shown in FIGS. 5 and 6 is shown in FIG. 24.

Referring to FIG. 24, the patch folder and press control circuit 862 includes the photocell 256, which is shown in the upper left-hand portion of FIG. 24, and a lamp 864. The lamp 864 shines light on the photocell 256 at all times except when a patch blocks the path between the lamp and photocell. The photocell 256 is connected to a photocell circuit 866 whose function is to produce a +26 volts DC signal on its output terminal 882 when a patch is between the lamp 864 and the photocell 256, and to connect terminal 882 to ground through a resistor 880 at all other times.

The photocell circuit 866 includes a variable resistor 868 for adjusting the sensitivity of the photocell circuit, and a conventional Schmitt trigger circuit 870 including transistors 872 and 874. The output of the Schmitt trigger circuit passes through a delay circuit 876 to the base of a switching transistor 878 whose collector is connected through the resistor 880 to ground, and whose emitter is connected to the +26 volts DC supply. The output terminal 882 is connected directly to the collector of switching transistor 878.

When a patch is not in a blocking position and light is allowed to reach photocell 256, transistor 872 is on, transistor 874 is off and transistor 878 is off, effectively connecting output lead 882 to ground through resistor 880. When a patch blocks the light path between the lamp 864 and the photocell 256, the resistance of the photocell increases to a very high value from its previous very low value, thus turning off transistor 872, turning on transistor 874, and turning on transistor 878 so as to connect lead 882 to the 26 volts DC supply. The delay circuit 876 is provided in order to delay operation of circuit 866 and thus give the patch material a little time to settle in position after its arrival at the folding and pressing station.

Switches 884 and 886 in the upper middle portion of FIG. 24 are micro-switches which are operated when the press is in the process of pressing a folded patch. When the press is not in operation, the contact arms are in the positions shown in FIG. 24 so as to connect the coil of a relay K₅ to the output lead 832 of a delay circuit 822 which receives the output signal from output lead 882 of the photocell circuit 866. Delay circuit 822 is identical to the circuit bearing the same reference numeral in FIG. 23. The output lead 832 accordingly is connected to ground when the signal on lead 882 rises to 26 volts in response to the presence of a patch in blocking position. Thus, relay K₅ is operated after the delay provided by circuit 876.

Referring now to the lower right-hand portion of FIG. 24, the energization of relay K₅ connects one terminal of the patch folder "down" valve solenoid 900 to ground. The other terminal is connected to a 117 volt AC source, so that the cylinder 251 shown in FIG. 5 is operated to bring the folder blade down to fold the patch.

The relay K₅ remains energized for a time period determined by the setting of the delay circuit 822, and then the circuit 822 causes the relay K₅ to become de-energized. This de-energizes the "down" valve solenoid 900 and energizes the patch folder "up" valve solenoid 898 to return the patch folder blade to its starting position.

The patch folder micro-switch 267 is in the position shown only when the folder blade is all the way up, and is switched to its other condition whenever the folder blade is elsewhere. A series resistor 896 and capacitor 894 are connected between the contact arm of switch 267 and ground. When the contact arm of 267 is moved into contact with point 892 upon depression of the folder blade, the resistor 896 and capacitor 894 are connected between ground and the output lead 882 of the photocell circuit 866. Thus, +26 volts is applied to charge the capacitor 894 while the folder blade is descending and ascending.

When the folder blade returns to its upper-most position, the capacitor 894 and resistor 896 again are connected to the left terminal of switch 267, and through contact 890 of relay K₅ to another delay circuit 822 which operates to connect the lower terminal of the coil of relay K₆ to ground, thus energizing relay K₆. This connects the lower terminal of the "press" valve solenoid 902 (in the lower right hand corner of FIG. 24) to ground, thus energizing the press valve and causing the patch to be pressed in the manner described above.

After a pre-determined time set by the delay circuit 822, the relay K₆ is de-energized and the pressing operation is stopped.

When the pressing operation is completed, it is desired to operate the folder blade again to push the folded patch out of the press and drop it down onto the conveyor to take it to the next station. This is accomplished by the following means. A switching circuit 888 is provided. The switching circuit 888 includes a conventional delay circuit 887 connected to the upper terminal of relay coil K₅ by a lead 893. The delay circuit 887 is connected to the base of a transistor 885 which is connected to another transistor 883. A series resistor and capacitor 895 are connected between ground and the emitter lead of transistor 883. During the pressing operation, a +26 volt signal is applied through line 889 from the circuit 822 to charge the capacitor 895. At this time, there is no input signal on line 893 so that transistor 885 is turned off, as is transistor 883.

When both of the press switches 884 and 886 are returned to their normal positions after the pressing operation, they once again connect line 893 to +26 volts, thus turning on transistor 885 and allowing capacitor 895 to discharge through the emitter-collector path of transistor 883, through an output lead 891, to the input lead 882 of delay circuit 822.

This causes the relay K₅ to operate again and will cause the folder blade to descend and ascend once again to push the folded patch out from between the press blocks. It should be noted, however, the pressing mechanism does not operate again at this time because, just as soon as the patch is folded by the first movement of the folder blade, the photocell 256 is uncovered so that transistor 878 is turned off. Therefore, when the switch 267 operates, the capacitor 894 will not be charged, and the pressing circuitry will not operate again.

ZIPPER FEED CONTROL CIRCUIT

The electrical circuit used to control the zipper feed mechanism shown in FIG. 8 is shown in FIG. 25.

Referring to FIG. 25, the zipper feed control circuit 904 includes a lamp 906 and the photocell 327. The zipper string loop shown in FIG. 22 either blocks light from the lamp 906 and prevents it from reaching the

photocell 327, or it does not, depending on the length of the loop. The photocell 327 is connected to a photocell circuit 866 which operates to ground the lower terminal of relay coil K₇ when light reaches photocell 327, thus energizing relay K₇, and disconnects from ground when the light is prevented from reaching photocell 327, to de-energize the relay K₇.

The operation of relay K₇ energizes the zipper feed motor 317 with 117 volts AC, if the relay contacts K₈ shown in FIG. 5 also are actuated, so that the right hand terminal of motor 317 is connected to ground. The coil for relay K₈ is part of the serger control circuit, and is shown in FIG. 26. This means that the zipper will not be fed by the zipper feed motor 317 unless the serger is operating.

The circuit 904 prevents the feeding of the zipper tape when the bottom of the tape loop is below a predetermined level, and thus signifies a lack of demand for the tape.

The circuit 866 provides a certain amount of time delay in both energizing and de-energizing the relay K₇. Thus, a "deadband" is created so as to prevent unnecessarily frequent operation of the circuit 904.

SERGER CONTROL AND START CIRCUIT

FIG. 26 shows the circuit for controlling the serger mechanism and the circuit for developing a start signal to start each cycle of operation at the subsequent processing stations.

Referring to FIG. 26, the serger control and start circuit 907 includes a lamp 908 and the photocell 372, with a photocell circuit 866 as in FIGS. 24 and 25. When a patch first covers the photocell 372, the circuit 866 grounds the lower terminal of the coil of relay K₈, thus completing the circuit between the +26 volt source and ground through the coil. This actuates contacts K₈ (in the lower portion of FIG. 26) to energize the serger motor sew valve solenoid 916 to start the serger motor. When the patch uncovers the photocell 372, the circuit 866 disconnects coil K₈ from ground, opening contacts K₈, and energizing both the serger motor brake valve solenoid 912 and the serger presser foot valve solenoid 914, thus stopping and braking the serger motor, operating the presser foot, and completing the serging operation.

When the patch first is detected, a delay circuit 910 is actuated which, after a delay to allow the patch material to settle, produces an output signal on the start signal output line 918. A signal is delivered over line 918 to the puller and gapper control circuit 909 shown in FIG. 27, and to subsequent processing stations to start another cycle of operation at each station.

PULLER AND GAPPER CONTROL CIRCUIT

FIG. 27 shows the electrical circuitry for controlling the puller shown in FIG. 16, as well as the gapper mechanism.

Referring to FIG. 16 as well as FIG. 27, both a large motor 484 for fast drive and a small motor 497 for slow drive are provided. As is shown at the bottom of FIG. 27, both motors 484 and 497 are energized and run continuously during operation of the system. The clutch 491 shown in FIG. 16 is operated electrically. When it is de-energized, it couples belt 489 from motor 484 to the gear box 500 to drive the rolls 480 and 481. When the clutch 491 is energized, it couples the small

motor 497 to the gear box to drive the rolls at a slower speed preparatory to stopping.

The large motor 484 has an internal clutch-brake which is operated by an air cylinder. The solenoid valve 946 for the air cylinder is shown in the lower left-hand portion of FIG. 27, but not in FIG. 16. This solenoid valve operates the air cylinder which operates a clutch in the motor 484 to couple its drive shaft with the belt 489. Thus when the electric clutch 491 and solenoid valve 946 are not energized, both motors 484 and 497 are running but do not drive the puller mechanism. When solenoid valve 946 is energized, this couples the large drive motor 484 to the gear box 500 for fast pulling action. When the solenoid valve 946 is de-energized, the brake solenoid valve 944 for motor 484 is energized to stop the drive pulley of motor 484. Also, the solenoid 930 (upper right hand corner of FIG. 27) of the electric clutch 491 is energized. This couples the slow drive motor 497 to the gear box 500 for slow pulling. Subsequently, the clutch 491 is de-energized to stop the patch at the proper location for gapping.

Now referring to the upper portion of FIG. 27, the puller is started either manually by closing the gapper advance switch 926 or, preferably, automatically by the receipt of a start signal over the line 918 through a switch 920 operable manually to select the automatic mode of operation. The switches 926 and 920 are shown in the position for automatic operation. In either mode of operation, a +26 volt DC signal is delivered through a relay driver circuit 922 to ground the lower terminal of a relay coil K₉.

Relay K₉ will be energized if and only if each of switches 402, 407 and 927 is closed to connect the upper terminal of coil K₉ to the positive 26 volt supply. The switch 927 is the manually operated gapper switch. The switch 407 is the lower limit switch for the take-up wheel 397 shown in FIG. 11, and switch 402 is the upper limit switch for the take-up wheel 397. However the lower limit switch actually is located at the take-up station between the gapper station and the top stop station. The operation of relay K₉ energizes solenoid valve 946 to start the positive pulling of material through the take-up station shown in FIG. 11. However, the motor will not run if the take-up wheel 397 at the take-up station between the serger and gapper stations is so high that it closes switch 402. The motor also will not run if the take-up wheel at the next take-up station between the gapper and top stop stations is so low that it closes switch 407. Thus, the puller will not pull fabric when the preceding machine is lagging behind the subsequent processing equipment. The puller also will not operate if the next machine in the system is lagging behind so that there is an excessive accumulation of material at the take-up station following the gapper. Thus, the system advantageously automatically adjusts for variations in the production speed of the various components in the entire system, thus minimizing labor needed to watch and maintain the system.

In the operation of the gapper mechanism, a lamp 430 is positioned so as to shine light upon the photocell 430a (see FIG. 13, as well as the upper portion of FIG. 27) which is connected to a photocell circuit 866 whose operation has been described above. A short time after the leading edge of the patch moves into the gapper station and covers the photocell 430a, the circuit 866 delivers a pulse to a switching circuit 852 (identical to the circuit 852 in FIG. 23) which operates

another switching circuit 928 to energize the solenoid 930 of the electric circuit 491 shown in FIG. 16. The switching circuit 928 is disabled unless the gapper-puller clutch-brake microswitch 490 is closed. The switch 490 is shown in FIG. 18. The switch 490 is closed only when the solenoid valve 944 (lower left corner of FIG. 27) is actuated to brake the motor 484 after its clutch has been disengaged. The switching circuit 928 therefore first sends a signal over lead 954 back to the relay driver circuit 922 to disconnect relay coil K₉ from ground and de-energize the relay. This causes a reversal of the contacts of relay K₉, thus de-energizing solenoid valve 946 and energizing the brake solenoid valve 944 to brake the motor 484. When the brake is engaged, the switch 490 closes, and the solenoid 930 of clutch 491 is energized. This causes the patch to move at a reduced speed under the control of the motor 497 for a short time preparatory to stopping.

The leading edge of the patch next is detected when it covers the photocell 434a to block light received from the lamp 434. This de-activates the photocell 434a and causes the sending of a signal from a photocell circuit 866 to a timer 936. The circuit 852a is identical to the circuit 852 and includes a timer which produces a precisely timed signal which is delivered over a lead 956 to the switching circuit 852. This de-energizes the switching circuit 928, causing it to de-energize the clutch solenoid 930, thus stopping the patch at the desired position with a high degree of position.

A pulse circuit 938 is provided. The pulse circuit 938 is essentially identical to circuit 888 shown in the upper right hand corner of FIG. 24. A lead 958 connects the output of the switching circuit 852 to the pulse circuit 938 to charge a capacitor therein. When the output from switching circuit 852 is removed, the capacitor in circuit 938 discharges and delivers a pulse to a timer circuit 940. The timer circuit 940 is similar to the circuit 840 shown in FIG. 23. After a time delay, and while the remaining circuit elements are prepared for the next cycle of operation, circuit 940 energizes the coil of a relay K₁₀, and then, after a pre-determined time, de-energizes the coil K₁₀.

The energization of the relay K₁₀ causes the energization of the gapper trip valve solenoid 948 (in the lower portion of FIG. 27) to start the mechanical operation of the gapper device.

The turning off of the timer 940, signifying the end of the gapper cycle, supplies a signal over a lead 960 to a timer 942 which operates the coil of a relay K₁₁. This closes the contacts of relay K₁₁ and energizes the gapper air blast valve solenoid 950 to create a short air blast to blow away the cut zipper teeth. After a short time, the timer 942 de-energizes the relay K₁₁.

Switches 936 and 952 are provided to enable the gapper to be operated manually.

TOP STOP CONTROL CIRCUIT

The top stop control circuit is identical to the circuit 909 shown in FIG. 27, except that micro-switches for detecting the gaps in the zipper teeth are used in place of the photocells 430a and 434a in FIG. 27, and the mechanism applies a top stop instead of gapping the zipper teeth. As in the circuit 909, the puller in the top stop station will not pull material through the station if either the upper limit switch 402 at the preceeding

take-up station, or the lower limit switch 407 of the next take-up station is actuated.

Because of the identity of structure and operation, except for the differences noted above, the top stop control circuit is not shown or described in detail.

ZIPPER CUTTER CONTROL CIRCUIT

The zipper cutter control circuit also is identical to the circuit 909 shown in FIG. 27, with the exceptions that instead of both an upper limit switch 402 and a lower limit switch 407, only an upper limit switch 402 is used. The reason for this is that there is no need for a take-up station following the zipper cutter station, and there is no need for a lower limit switch. Switch 407 is used to control excessive accumulation of material at the output of the zipper cutter.

This circuit also will not be described in any greater detail because of the identity between it and the puller and gapper control circuit 909.

ZIPPER STACKER CONTROL CIRCUIT

The zipper stacker control circuit is known. A suitable circuit is described, for example, in the previously-mentioned U.S. Pat. No. 3,611,957 in which a similar stacker mechanism is disclosed.

BUTTON STAY SIDE ZIPPER PATCH MACHINE ELECTRICAL CONTROL CIRCUITRY

The above-described control circuitry can be used, with appropriate modification, to control the operation of the button stay-side zipper patch machine shown in FIG. 20. Additionally, the sewing machine 370 and the control circuit for it is interconnected with the run-out micro-switch 708 in a conventional manner.

With respect to the fly-side zipper patch machine, the control means for the two needle flat bed sewing machine 713 are interconnected with the feed device 60 and its control circuit. Moreover, as mentioned before, the intermittent feed is achieved by synchronizing the feed dog puller wheel 480 for the sewing machine 713 via the intergearing device 713a shown in FIG. 22. The intergearing device 713a makes the feed dog in sewing machine 370 shown in FIG. 21 unnecessary. Consequently, for the fly side zipper match machine the control means for the sewing machine 713 is interconnected with the control means for feed device 60, sewing machine 370 and the run-out micro-switch 655, and apart from this modification (which is conventional), the control circuits for the fly-side zipper patch machine are adaptable from the button stay side machine.

The above description of the invention is intended to be illustrative and not limiting. Various changes or modifications in the embodiments described may occur to those skilled in the art and these can be made without departing from the spirit or scope of the invention.

What is claimed is:

1. A zipper patch forming and sewing machine, the combination comprising:
means for feeding a patch to a sewing machine;
means for feeding a zipper string;
means for feedingly joining said zipper string with said patch;
means for guidingly and feedingly serging said zipper string to said patch, said means for feeding said patch and said means for feeding said zipper string being operatively interconnected with said means for serging;

a first means for guiding said zipper string and patch sewn to it including means for turning outwardly said zipper, said means for guiding being operatively interconnected with said means for serging; means for gapping said zipper string including a first means for feeding said zipper string and patch, means for slowing and stopping said first means for feeding of said zipper string and said patch whereby a segment of said zipper teeth on said zipper string is properly placed in said means for gapping and removed therefrom by said means for gapping when said means for feeding is stopped, said means for gapping being operatively interconnected with said means for serging and first means for guiding said zipper string and patch sewn thereto; 15

a second means for guiding said zipper string and patches, said second means for guiding being operatively interconnected with said means for gapping; means for placing a top stop on said zipper string including a second means for feeding said zipper string and said patch sewn thereto, a second means for slowing and stopping said second means for feeding of said zipper string and said patch whereby said zipper string is properly placed in said means for placing a top stop on said zipper string and a top stop is placed on said zipper string when said second means for feeding is stopped, said means for placing a top stop being operatively interconnected with said means for gapping, said second means for feeding and stopping and means for placing a top stop on said zipper string being further operatively interconnected with said second means for guiding; 20

a third means for guiding said zipper string and patch, said third means for guiding being operatively interconnected with said means for placing a top stop on said zipper string; 25

means for cutting of said zipper string including a third means for feeding said zipper string and said patch sewn thereto, a third means for slowing and stopping of said third means for feeding whereby said zipper string is placed in a proper cutting position, means for removing a patch from said zipper string, said third means for guiding being operatively interconnected with said third means for feeding and stopping and means for cutting said zipper string; and 30

means for stacking said patch with a cut zipper string, said means for stacking being operatively interconnected with means for removing said cut patch from said means for cutting. 35

2. A zipper patch forming and sewing machine, the combination comprising:

means for feeding a succession of patches to a serging machine including means for inverting a series of patches within said succession of patches and means for folding each of the patches; 40

means for feeding a zipper string; 45

means for guidingly and feedingly serging said zipper string to said succession of patches, said means for feeding said patches and said means for feeding said zipper string being operatively interconnected with said means for serging; 50

a first means for guiding said zipper string and said patches sewn to it including means for turning outwardly said zipper teeth, said means for guiding 55

being operatively interconnected with said means for serging; means for gapping said zipper string including a first means for feeding said zipper string and patches, means for slowing and stopping said feeding of said zipper string and said patches whereby a segment of said zipper teeth on said zipper string is properly placed in said means for gapping and removed therefrom by said means for gapping when said means for feeding is stopped, said means for gapping being operatively interconnected with said means for serging and first means for guiding said zipper string and patches sewn thereto; a second means for guiding said zipper string and patches, said second guide means being operatively interconnected with said means for gapping; means for placing a top stop on said zipper string including a second means for feeding said zipper string and said patches sewn thereto, a second means for slowing and stopping said second means for feeding of said zipper string and said patches whereby said zipper string is properly placed in said means for placing a top stop on said zipper string and a top stop is placed on said zipper string when said second means for feeding is stopped, said means for placing a top stop being operatively interconnected with said means for gapping, said second means for feeding and stopping and means for placing a top stop on said zipper string being further operatively interconnected with said second means for guiding; 20

a third means for guiding said zipper string and patches, said third means for guiding being operatively interconnected with said means for placing a top stop on said zipper string; 25

means for cutting of said zipper string between two patches including a third means for feeding said zipper string and said patches sewn thereto, a third means for slowing and stopping of said third means for feeding whereby said zipper string is placed in a proper cutting position and means for removing a patch with a cut zipper string from said zipper string, said third means for guiding being operatively interconnected with said third means for feeding and stopping and means for cutting said zipper string in a proper position; and 30

means for stacking said patch with a cut zipper string including means for removing said patch from said means for cutting. 35

3. A zipper patch forming and sewing machine, the combination comprising:

a serging sewing machine; 40

means for repetitive feeding of a series of patches to said serging machine including means for raising and lowering a stack of patches in a first pickup position, means for picking up a top patch from said stack of patches; means for transferring said top patch from said stack of patches and depositing said top patch in a second, transfer position; means for reciprocating said means for transferring between said first pickup position and said second, transfer position; means for detaching said top patch from said means for transferring at said second, transfer position; means for returning said means for transferring to said first pickup position including means for activating said means for pick- 45

ing up said top patch and means for initiating a repetitive pickup and transfer work cycle; means for conveying each detached patch; means for folding a patch operatively interconnected with said means for conveying said detached patch; 5 means for conveying said folded patch into said serging machine; means for feeding a zipper string having zipper teeth thereon into said serging machine including means for sensing said feeding of said zipper string, said 10 means for sensing being operatively interconnected with said means for feeding of said zipper and said serging machine; means for urging said patch and said zipper string sewingly through said sewing machine whereby said zipper and said patch is sewn together and each of said repetitively fed patches is sewn to said zipper string in a string of patches; 15 a first guide means for said zipper string and said patches including a guide wheel movable between a first signal position and a second signal position and means for folding said zipper string whereby said teeth on said zipper string form one edge of said continuous string of patches, 20 a first means for intermittent feeding of said zipper string and patches; means for gapping a segment of zipper teeth in said zipper string including means for adjusting said segment within a single tooth position, said means for gapping being operatively interconnected with said 30 first means for intermittent feeding of said zipper string and patches whereby said zipper string is predeterminedly positioned for gapping said means for gapping being further operatively interconnected with said first signal position and second signal position on said first guide means for said zipper string and patches whereby the means for gapping is deactivated when first signal position is activated and said gapping means is activated when said second signal position is activated; 40 a second guide means for said zipper string and patches including a second guide wheel movable between a third signal position and a fourth signal position; 45 a second means for intermittent feeding of said zipper string and patches; means for placing a top stop on said zipper string including means for placing said zipper string in a predetermined position, said means for placing a top stop being operatively interconnected with said second means for intermittent feeding of said zipper string and patches, said means for placing a top stop being further operatively interconnected with said third signal position and fourth signal position on said second guide means for said zipper string and patches, whereby the means for placing a top stop is deactivated when said third signal position is activated and said means for placing a top stop is deactivated when said fourth signal position is activated; 55 a third guide means including a third guide wheel movable between a fifth signal position and a sixth signal position; a third means for intermittent feeding of said zipper string and patches; 60 means for cutting said zipper string including means for placing in cutting position said zipper string,

said means for placing in cutting position said zipper string being operatively interconnected with said third means for intermittent feeding of said zipper string and patches, said means for cutting being further operatively interconnected with said fifth signal position and sixth signal position of said third guide means; and means for removing a zipper patch with a cut zipper string from said means for cutting said zipper string including means for stacking of same. 4. The zipper patch forming and sewing machine as defined in claim 1 and wherein the means for feeding a patch to the sewing machine comprises a motor, a shaft extension on said motor, a plurality of pinions on said shaft extension, a plurality of racks interconnected with said pinions, a table on top of said racks, means for activating said motor for a left hand and right hand rotation of said shaft whereby said table is reciprocated upwardly and downwardly, a fixed frame member, a plurality of rails above said table extending beyond said table and mounted in said fixed frame member, a carriage slideably mounted on said rails, said carriage including a supply reel, an engagement wheel, a takeup reel, an adhesive tape on said supply reel interconnected via said engagement wheel to said takeup reel, a drive gear, a vertical frame member, a plurality of shafts on said vertical frame member comprising a first shaft for said supply reel, a second shaft for said engagement wheel, a third shaft for said takeup reel, a fourth shaft for said drive gear, said drive gear being operatively interconnected with said takeup reel; means for reciprocating said carriage on said rails between a pickup position and a transfer position, means for incrementally driving said drive gear on reciprocation of said carriage between said pickup and transfer position; and means for activating said rotation of said motor operatively interconnected with said carriage in said pickup position including means for initiating a pickup and transfer work cycle whereby a patch is picked off said table by said tape on said engagement wheel for transfer to said serging machine. 5. The zipper patch forming and sewing machine as defined in claim 1 and wherein the means for feeding a patch to the sewing machine comprises: a motor, a shaft attached to said motor, a plurality of pinions on said shaft, a plurality of racks interconnected with said pinions, a table attached to a vertical top part of said racks, means for activating said motor for a left hand and right hand rotation of said shaft whereby said table is reciprocated upwardly and downwardly, a guide means for said table adjacent to one side thereto, a guide means for said table at one end thereof, a vertical end part for said table, a fixed frame member, a plurality of rails directly above said table extending beyond said table and mounted in said fixed frame member, a carriage mounted on said rails, said carriage including a cross member, means for operably engaging said plurality of rails, said means for engaging said rails being interconnected to said cross member, a supply reel, an engagement wheel, a takeup reel, an adhesive tape on said supply reel interconnected via said engagement wheel to said takeup reel, a driven gear, a drive gear, a vertical carriage frame member attached to said cross member, a plurality of shafts on said vertical

frame member comprising a first shaft for said supply reel, a second shaft for said engagement wheel, a third shaft for said takeup reel, a fourth shaft for said drive gear and for said driven gear, said drive gear being operatively interconnected with said takeup reel; means for reciprocating said carriage on said rails between a pickup position and a transfer position, a first frame member fixedly attached to said fixed frame member, including means for driving said driven gear operatively interconnected with said carriage and said driven gear thereon whereby said driven gear is incrementally advanced when said carriage is reciprocated between said pickup and transfer position; and means for activating said rotation of said motor operatively interconnected with said carriage in said pickup position including means for initiating a pickup and transfer work cycle whereby a patch is picked off said table by said tape on said engagement wheel for transfer to said serging machine.

6. The machine as defined in claim 5 including means for maintaining repetitive work cycles.

7. The machine as defined in claim 5 including means for aiding in separation of said patch from a next patch on said work table.

8. The machine as defined in claim 5 including means for removing a patch from said tape on said engagement wheel of said carriage at said transfer position.

9. The zipper patch forming and sewing machine as defined in claim 1 including means for folding the patches prior to said patches being joined with said zipper string by said means for feedingly joining, said feeding means comprising a conveyor, a motor for said conveyor, a first, a second and a third section of said conveyor, means for interlinking said first, second and third sections of said conveyor whereby each section of said conveyor moves a work piece thereon at a similar velocity; said second and third conveyor sections being located adjacent each other and being spaced apart by an aperture therebetween in the feed direction of said first conveyor section; a frame over said second and third conveyor sections and said aperture; a blade slidably mounted in said frame in vertical alignment with said aperture; means for urging downwardly and upwardly said blade whereby said blade is slidably dependent from said frame; means for sensing the presence of a patch on said second and third conveyor sections over said aperture; means for activating at least once said means for urging downwardly said blade whereby said blade is pushed into engagement with a patch over said aperture and then enters the aperture with the patch to fold the patch in said aperture; means for pressing said patch in said aperture and means for conducting said patch from said aperture for feeding the same to said sewing machine.

10. The machine as defined in claim 9 and comprising a frame over said first conveyor section and a means for inverting a patch on said conveyor dependent from said frame.

11. The zipper patch forming and sewing machine as defined in claim 1 including means for folding the patch prior to the patch being joined with said zipper string by said means for feedingly joining, said folding means comprising a conveyor having a plurality of interlinked conveyor rollers in first, second and third sections; a motor for driving said interlinked conveyor rollers; an edge guide for a patch on said first and second sections of said conveyor rollers; said second and

third conveyor sections being located adjacent each other and being spaced apart by an elongated aperture therebetween extending in the feed direction of said conveyor rollers; a blade insertable in said aperture; a frame over said second and third conveyor sections and said aperture wherefrom said blade is slidably dependent; means for reciprocating said blade downwardly and upwardly; means for sensing the presence of a patch on said second and third conveyors over said aperture; means responsive to said sensing means for activating said means for reciprocating said blade to move said blade downwardly into engagement with a patch over said aperture detected by said sensing means and thence into said aperture with said patch, whereby said patch is folded in said aperture; a heated bar forming a part of the first side of said aperture; a slidable bar forming a part of the second side of said aperture; means for urging said slidable side bar against a patch in said aperture and said heated bar operatively interconnected with said means for reciprocating said blade; means for removing said slidable bar from said patch and heated bar whereby a folded and pressed patch is obtained; a chute member at the bottom of said aperture at one side thereof and means for conveying said folded and pressed patch to said sewing machine.

12. The zipper patch forming and sewing machine as defined in claim 1 and wherein the means for feeding a patch to said sewing machine comprises a shaft, a disc mounted on said shaft for a roll of individual patches attached on a backing material, means for folding said patches and means for feeding said patches into said sewing machine.

13. The zipper patch forming and sewing machine as defined in claim 1 and wherein the means for feeding said zipper string includes a detection means for indicating a zipper string exhaustion; and a detection means for indicating a zipper string jam up in the feeding means.

14. A fly side zipper patch sewing and forming machine the combination comprising:

a serging sewing machine;
means for feeding a patch and a backing material into said serging sewing machine including means for detecting an exhaustion of said patches and backing material and means for guiding said patches and said material;
a two needle flat bed sewing machine;
means for feeding a zipper string to said two needle sewing machine;
means for guiding said zipper string and said patches and backing material in said two needle machine;
means for intermittent pulling of said zipper string, backing material and said patches operatively interconnected with said two needle sewing machine and said serging sewing machine in an operative sewing mode and inoperatively interconnected in an inoperable sewing mode of said two needle sewing machine and said serging machine;
means for engaging said means for intermittent pulling and means for disengaging said means for intermittent pulling;
a first guide means for said zipper string and said patches including a guide wheel movable between a first signal position and a second signal position and means for folding said zipper string whereby the teeth on said zipper string form one edge of said continuous string of patches;

a first means for intermittent feeding of said zipper string and patches;

means for gapping a segment of zipper teeth in said zipper string including means for adjusting said segment within a single tooth position, said means for gapping being operatively interconnected with said first means for intermittent feeding said zipper string and patches whereby said zipper string is predeterminedly positioned for gapping; said means for gapping being further operatively interconnected with said first signal position and second signal position on said first guide means for said zipper string and patches whereby the means for gapping is deactivated when said first signal position is activated and said gapping means is activated when said second signal position is activated;

a second guide means for said zipper string and patches including a second guide wheel movable between a third signal position and a fourth signal position;

a second means for intermittent feeding of said zipper string and patches;

means for cutting said zipper string including means for placing in cutting position said zipper string, said means for placing in cutting position said zipper string being operatively interconnected with said second means for intermittent feeding of said zipper string and patches, said cutting means being further operatively interconnected with said third signal position and fourth signal position of said second guide means;

and means for removing a zipper patch from said means for cutting said zipper string including means for stacking of same.

15. A pickup and transfer device for a garment component, the combination comprising: a motor, a shaft extension on said motor, a plurality of pinions on said shaft extension, a plurality of racks interconnected with said pinions, a table for a stack of garment components attached on top of said racks, means for activating said motor for a left hand and right hand rotation of said shaft whereby said table is reciprocated upwardly and downwardly, a guide means for said garment component on said table adjacent to one side of said table, a guide means for said garment components on said table at one end of said table, a vertical end part for said table, a fixed frame member, a plurality of rails above said table extending beyond said table and mounted in said fixed frame member, a carriage slideably mounted on said rails, said carriage including

a supply reel, an engagement wheel, a takeup reel, an adhesive tape on said supply reel interconnected via said engagement wheel to said takeup reel, a drive gear, a vertical frame member, a plurality of shafts on said vertical frame member comprising a first shaft for said supply reel, a second shaft for said engagement wheel, a third shaft for said takeup reel, a fourth shaft for said drive gear, said drive gear being operatively interconnected with said takeup reel;

means for reciprocating said carriage on said rails between a pickup position and a transfer position, means for incrementally driving said drive gear on reciprocation of said carriage pickup and transfer position; and means for activating said rotation of said motor operatively interconnected with said carriage in said pickup position including means

for initiating a pickup and transfer work cycle whereby a garment component is picked off said table by said tape on said engagement wheel and transferred to a next work station.

5 16. A folder for garment components as a work piece, the combination comprising: a conveyor; a motor for said conveyor; a first, a second and a third section of said conveyor; means for interlinking said first, second and third sections of said conveyor whereby said conveyor moves said work piece on each section at a similar velocity; said second and third conveyor sections being located adjacent each other and being spaced apart by an aperture therebetween in the feed direction of said first conveyor section; a frame 10 over said second and third conveyor sections and said aperture; a blade slidably mounted in said frame in vertical alignment with said aperture; means for urging downwardly and upwardly said blade whereby said blade is slidably dependent from said frame; means for 15 sensing the presence of a patch on said second and third conveyor sections over said aperture; means for activating at least once said means for urging downwardly said blade whereby said blade is pushed into engagement with a patch over said aperture and then enters the aperture with the patch to fold the patch in said aperture; means for pressing said patch in said aperture and means for conducting said patch from said aperture for feeding the same to a subsequent work station.

17. A folder for garment components, the combination comprising: a conveyor having a plurality of interlinked conveyor rollers in first, second and third sections; a motor for driving said interlinked conveyor rollers, an edge guide for a patch on said first and second sections of said conveyor rollers, said second and third conveyor sections being located adjacent each other and being spaced apart by an elongated aperture therebetween extending in the feed direction of said conveyor rollers; a blade insertable in said aperture; a frame over said second and third conveyor sections and said aperture wherefrom said blade is slidably dependent; means for reciprocating said blade downwardly and upwardly; means for sensing the presence of a patch on said second and third conveyors over said aperture; means responsive to said sensing means for activating said means for reciprocating said blade to move said blade downwardly into engagement with a patch over said aperture detected by said sensing means and thence into said aperture with said patch, whereby said patch is folded in said aperture; a heated bar forming a part of the first side of said aperture; a slideable bar forming a part of the second side of said aperture; means for urging said slideable side bar against a patch in said aperture and heated bar operatively interconnected with means for reciprocating said blade; means for removing said slideable bar from said patch and heated bar whereby a folded and pressed patch is obtained; a chute member at the bottom of said aperture at one side thereof and means for conveying said folded and pressed patch to a subsequent work station.

40 18. A pickup, transfer and fold device for a garment component, the combination comprising: a motor, a shaft extension on said motor, a plurality of pinions on said shaft extension, a plurality of racks interconnected with said pinions, a table for a stack of garment components attached on top of said racks, means for activating said motor for a left hand and right hand rotation of said shaft whereby said table is reciprocated up-

wardly and downwardly, a guide means for said garment component on said table adjacent to one side of said table, a guide means for said garment components on said table at one end of said table, a vertical end part for said table, a fixed frame member, a plurality of rails above said table extending beyond said table and mounted in said fixed frame member, a carriage slidably mounted on said rails, said carriage including a supply reel, an engagement wheel, a takeup reel, an adhesive tape on said supply reel interconnected via said engagement wheel to said takeup reel, a drive gear, a vertical frame member, a plurality of shafts on said vertical frame member comprising a first shaft for said supply reel, a second shaft for said engagement wheel, a third shaft for said takeup reel, a fourth shaft for said drive gear, said drive gear being operatively interconnected with said takeup reel means for reciprocating said carriage on said rails between a pickup position and a transfer position; means for incrementally driving said drive gear on reciprocation of said carriage between said pickup and transfer position; means for activating said rotation of said motor operatively interconnected with said carriage in said pickup position including means for initiating a pickup and transfer work cycle whereby a garment component is picked off said table by said tape on said engagement wheel; a conveyor having a plurality of interlinked conveyor rollers having first, second and third sections; a motor for driving said interlinked conveyor rollers; means for detecting said carriage over said conveyor; means for transferring said garment component to said first conveyor section; an edge guide for a patch on said first and second sections on said conveyor rollers; said second and third conveyor sections being located adjacent each other and being spaced apart by an elongated aperture therebetween extending in the feed direction of said conveyor rollers; a blade insertable in said aperture; a frame over said second and third conveyor sections and said aperture wherefrom said blade is slidably dependent; means for reciprocating said blade downwardly and upwardly; means for sensing the presence of a patch on said second and third conveyors over said aperture; means responsive to said sensing means for activating said means for reciprocating said blade to move said blade downwardly into engagement with a patch over said aperture detected by said sensing means and thence into said aperture with said patch, whereby said patch is folded in said aperture; a heated bar forming a part of the first side of said aperture; a slidable bar forming a part of the second side of said aperture; means for urging said slidable bar against a patch in said aperture and said heated bar operatively interconnected with means for reciprocating said blade; means for removing said slidable bar from said patch and heated bar whereby a folded and pressed patch is obtained; a chute member at the bottom of said aperture at one side thereof and means for conveying said folded and pressed patch to a subsequent work station.

19. The device as defined in claim 18 and comprising a frame member over said first section of said conveyor rollers and, interconnected to said frame member,

means for inverting a work piece on said conveyor rollers.

20. A fly side zipper patch sewing and forming machine the combination comprising:

5 a serging sewing machine;

means for feeding a patch and a backing material into said serging sewing machine including means for guiding said patches and said material;

a two needle flat bed sewing machine;

means for feeding a zipper string to said two needle sewing machine;

means for guiding said zipper string and said patches and backing material in said two needle machine;

means for intermittent pulling of said zipper string, backing material and said patches including means for engaging said means for intermittent pulling and means for disengaging said means for intermittent pulling, said means for intermittent pulling being operatively interconnected with said two needle sewing machine and said serging sewing machine in an operative sewing mode and inoperatively interconnected in an inoperable sewing mode of said two needle sewing machine and said serging machine;

a first means for guiding said zipper string and patches sewn to it including means for turning outwardly said zipper string, said means for guiding being operatively interconnected with said two needle sewing machine;

30 means for gapping said zipper string including a first means for feeding said zipper string and patches, means for slowing and stopping said first means for feeding of said zipper string and said patch whereby a segment of said zipper teeth on said zipper string is placed in said means for gapping and removed therefrom by said means for gapping when said means for feeding is stopped, said means for gapping being operatively interconnected with said means for sewing and said first means for guiding said zipper string and patches sewn thereto;

a second means for guiding said zipper string and patches, said second means for guiding being operatively interconnected with said means for gapping;

means for cutting of said zipper string including a second means for feeding said zipper string and said patches sewn thereto, a second means for slowing and stopping of said second means for feeding whereby said zipper string is placed in a proper cutting position, means for removing a patch with a cut zipper string from an uncut zipper string, said second means for guiding being operatively interconnected with said second means for feeding and stopping and means for cutting said zipper string;

45 and means for stacking said patch with a cut zipper string, said means for stacking being operatively interconnected with means for removing said patch with a cut zipper string from said means for cutting.

21. In a system for fabricating clothing parts, an elongated flexible part carrier comprising a zipper string with parts attached thereto at spaced intervals, means for fastening each of said parts to said zipper string in a first fabricating operation upon each of said parts at a first station, means for feeding said zipper string and parts to a second station for the performance of a further operation on said parts, means for forming a loop in said zipper string intermediate said first and second

stations, means for detecting the movement of the bottom of said loop above a certain predetermined position, means for disabling the feeding of said zipper string to said second station until said loop bottom drops below said predetermined level and means for severing said string at selected locations between said parts to form separate parts with attached zipper segments.

22. A system as in claim 21 including means for detecting and signaling the movement of said loop bottom below a second pre-determined position located below the first predetermined position.

23. A system as in claim 21 including means for applying tension to the portion of said zipper string in said loop.

24. A system as in claim 23 in which said tension applying means includes a weighted member hanging in said loop at the bottom thereof, and means for guiding said member in movement upwardly and downwardly with said loop bottom.

25. A system as in claim 24 in which said detecting means includes switch means engageable by said weighted member.

26. A system as in claim 24 in which said member is a wheel, and including means for partially counter-balancing the weight of said wheel.

27. A system as in claim 21 wherein said parts are pants fly parts, said further operation is the gapping of teeth on said zipper string, and said system includes third and fourth operating stations, means for forming a loop in said zipper string respectively located between each of the second and third and third and fourth stations, means associated with each of said last mentioned loop forming means for detecting the movement of the bottom of said loop above a certain predetermined position and means respectively responsive to said loop detecting means for disabling feeding of said zipper string to said third and fourth stations until the loops therebetween drop below said predetermined level; means at said third station for applying a top stop to the zipper adjacent each patch, and said means for severing said zipper string being located at said fourth station.

28. A system as in claim 27 including means at said first station for indicating the sewing of one of said parts to said zipper string and sending a corresponding start signal to start one cycle of operation of each of said top stop applying means and severing means and gapping means.

29. A fly side zipper patch sewing and forming machine the combination comprising:

first means for repetitive feeding of a series of patches including means for raising and lowering a stack of patches in a first pickup position, means for picking up a top patch from said stack of patches; means for transferring said top patch from said stack of patches and depositing said top patch in a second, transfer position; means for reciprocating said means for transferring between said first pickup position and said second, transfer position; means for detaching said top patch from said means for transferring at said second, transfer position; means for returning said means for transferring to said first pickup position including means for activating said means for picking up said top patch and means for initiating a repetitive pickup and transfer work cycle;

first means for placing a patch of said patches in a receiving position; second means for repetitive feeding of a series of backing material for said patches; second means for placing a backing of said backing material in a receiving position; means for mating each of said patches with a backing therefore;

a serging sewing machine including means operatively interconnected with said first and second means for repetitive feeding and means for mating; third means for repetitive feeding a mated patch and a backing material into said serging sewing machine for sewing therein including means for guiding said patches and said backing material; a two needle flat bed sewing machine;

means for feeding a zipper string to said two needle sewing machine;

means for guiding said zipper string and said patches and backing material in said two needle machine;

means for intermittent pulling of said zipper string, backing material and said patches including means for engaging said means for intermittent pulling and means for disengaging said means for intermittent pulling, said means for intermittent pulling being operatively interconnected with said two needle sewing machine in an operative sewing mode and inoperatively interconnected in an inoperative sewing mode of said two needle sewing machine;

a first means for guiding said zipper string and patches sewn to it including means for turning outwardly said zipper, said means for guiding being operatively interconnected with means for sewing; means for gapping said zipper string including a first means for feeding said zipper string and patches, means for slowing and stopping said first means for feeding of said zipper string and said patch whereby a segment of said zipper teeth on said zipper string is placed in said means for gapping and removed therefrom by said means for gapping when said means for feeding is stopped, said means for gapping being operatively interconnected with said means for sewing and said first means for guiding said zipper string and patches sewn thereto;

a second means for guiding said zipper string and patches, said second means for guiding being operatively interconnected with said means for gapping; means for cutting of said zipper string including a second means for feeding said zipper string and said patches sewn thereto, a second means for slowing and stopping of said second means for feeding whereby said zipper string is placed in a proper cutting position, means for removing a patch with a cut zipper string from an uncut zipper string, said second means for guiding being operatively interconnected with said second means for feeding and stopping and means for cutting said zipper string;

and means for stacking said patch with a cut zipper string, said means for stacking being operatively interconnected with means for removing said patch with a cut zipper string from said means for cutting.

30. The machine as defined in claim 1 and including means for automatic operation of said machine.

31. The machine as defined in claim 12 and including means for automatic operation of said machine.

32. The machine as defined in claim 20 and including means for automatic operation of said machine.

33. The machine as defined in claim 29 and including means for automatic operation of said machine.
